(57) **CLAIM**

The ornamental design for a sport glove, as shown and described.

DESCRIPTION

FIG. 1 is a top and front perspective view of a sport glove showing my new design;

FIG. 2 is a bottom plan view thereof;

FIG. 3 is a top plan view thereof;

FIG. 4 is a left side elevation view thereof; and,

FIG. 5 is a right side elevation view thereof.

The broken lines shown on the sport glove are understood to represent stitching. The fragmentary pattern of lines shown on the palm pads in FIG. 2 is understood to be repeated uniformly throughout the surface of the pads.
